(57) **CLAIM**

I claim the ornamental design for a removable media rack for exercise console, as shown and described.

DESCRIPTION

FIG. 1 is a front perspective view of a removable media rack for an exercise console;

FIG. 2 is a back perspective view thereof;

FIG. 3 is a front elevation view thereof;

FIG. 4 is a back elevation view thereof;

FIG. 5 is a right elevation view thereof;

FIG. 6 is a left elevation view thereof;

FIG. 7 is a top plan view thereof;

FIG. 8 is a bottom plan view thereof; and,

FIG. 9 is a front perspective view thereof depicting the embodiment in use with an exercise console.

The broken lines in the FIGURES showing portions of the removable media rack for exercise console depict environment and form no part of the claim.

1 Claim, 7 Drawing Sheets
